DESIGN FOR A COMBINED NURSING BOTTLE HOLDER, TIME INDICATOR, AND THERMOMETER

James Y. Taylor and Carl C. Taylor, Brownwood,
Tex.

Application August 26, 1939, Serial No. 86,904

Term of patent 7 years

To all whom it may concern:

Be it known that we, James Y. Taylor and Carl C. Taylor, citizens of the United States of America, residing at Brownwood, in the county of Brown and State of Texas, have invented a new, original, and ornamental Design for a Combined Nursing Bottle Holder, Time Indicator, and Thermometer, of which the following is a specification, reference being had to the accompanying drawing, forming part thereof.

Figure 1 is a perspective view of a combined nursing bottle holder, time indicator, and thermometer, showing our new design.

Figure 2 is an enlarged, fragmentary, plan view of the indicator portion, and

Figure 3 is a fragmentary underside plan view of the indicator portion.

The dominant feature of our invention consists in the time indicator and thermometer portion.

We claim:

The ornamental design for a combined nursing bottle holder, time indicator, and thermometer, as shown and described.

JAMES Y. TAYLOR.
